UNITED STATES PATENT OFFICE.

WILLIAM P. WILLSON, OF ARLINGTON, VERMONT, ASSIGNOR TO WILLIAM E. KIDDER,
OF KALAMAZOO, MICHIGAN.

REFRIGERATOR.

Application filed August 20, 1923. Serial No. 658,474.

To all whom it may concern:

Be it known that I, WILLIAM P. WILLSON, a citizen of the United States, residing at Arlington, county of Bennington, State of Vermont, have invented certain new and useful Improvements in Refrigerators, of which the following is a specification.

This invention relates to improvements in refrigerators.

10 The main objects of this invention are:

First, to provide an improved refrigerator having a refrigerating chamber adapted to maintain low temperatures and one or more provision chambers associated with a single 15 refrigerant chamber.

Second, to provide an improved refrigerator employing ice and a chemical which is adapted for maintaining very low temperatures.

20 Third, to provide an improved refrigerator in which the provision chambers are provided with effective circulation and at the same time are not in communication with the refrigerant chamber.

25 Objects pertaining to details and economies of construction and operation will definitely appear from the detailed description to follow.

I accomplish the objects of my invention 30 by the devices and means described in the following specification. The invention is clearly defined and pointed out in the claims.

A structure which is a preferred embodiment of my invention is clearly illustrated in 35 the accompanying drawing forming a part of this application, in which:

Fig. I is a front elevation of a refrigerator embodying the features of my invention comprising two provision chambers and a 40 refrigerating or low temperature chamber.

Fig. II is a plan view.

Fig. III is a vertical central section on a line corresponding to line 3—3 of Fig. IV.

Fig. IV is a transverse vertical section on a line 4—4 of Fig. III.

Fig. V is an enlarged detail view of one of the doors.

Fig. VI is a detail section showing the bottom circulation ports or openings and the 50 valves or closures regulating the same.

In the drawings the sectional views are taken looking in the direction of the little arrows at the ends of the section lines and similar numerals of reference refer to similar parts throughout the several views.

Referring to the drawing, my improved refrigerator comprises an outer casing preferably made up of an outer wall 1, an inner wall or lining 2 of metal and an insulating filling 3. The structural details of these 60 walls, however, form no part of my present invention.

The structure illustrated has provision 65 chambers 4 at the ends of the casing and a refrigerating or low temperature chamber 5 disposed centrally of the casing. The provision chambers have inner walls 6 with air circulation openings 7 at the top and 8 at the bottom, the openings 8 being controlled by the damper or valve 9.

The refrigerating chamber is provided 70 with an outer imperforate wall 10 and an inner perforate wall 11 spaced from the outer wall so that air may circulate freely through this inner wall.

The racks 12 are supported on cleats 13 75 on the inner wall and hooks 14 are provided on the cleats for the suspending of any desired articles.

The refrigerant chamber 15 is of U-shape, 80 that is, it embraces the opposed sides and bottom of the refrigerating chamber, the walls of the refrigerating chamber constituting the inner walls of the refrigerant chamber, its outer side walls 16 and bottom 85 17 being spaced from the refrigerating chamber walls. The side walls are preferably diverged downwardly so that the refrigerant is not likely to become wedged or clogged and should it adhere to the walls it 90 can be readily freed by pushing downward.

The walls 16 are disposed in spaced relation to the walls 6 coacting therewith to provide air circulating passages 18 communicating with the provision chambers in the 95 top through the openings 7 and at the bottom through the valve openings 8, so that the air circulates upwardly through the provision chambers and downwardly through the passages 18 in contact with the walls 100 of the refrigerating chamber, thereby cooling the air.

The bottom wall 17 of the refrigerating chamber is supported on the blocks 19 and a drain opening 20 is provided in the bottom of the casing so that any moisture condensed upon the wall 16 will, when not held in the form of frost thereon, drain into the bottom of the casing and out through the opening 20.

The refrigerant chamber is adapted to contain a liquid and has a level determining pipe 21, the upper end of which is preferably crooked as shown so that the liquid 5 serves as a seal when the liquid reaches the end of the pipe. A drain pipe 22 is provided for the refrigerant tank controlled by the valve 23.

The top 24 of the refrigerating chamber 10 is spaced from the upper edge of the refrigerator casing so that when the door or cover 25 of the refrigerating chamber is opened a hopper is provided for the refrigerant so that it may be dumped into this hopper and 15 pushed into the vertical portions of the refrigerating chamber.

The provision chambers are provided with doors 26 while the refrigerating chamber is provided with a door 27. By using 20 chipped ice or ground ice and a suitable chemical very low temperatures may be maintained in the refrigerating chamber and the desired temperatures may be maintained in the provision chambers, this temperature being controlled by the valves 9 25 controlling the circulation.

I preferably provide the doors 26 and 27 with jambs 28 and 29 each having thereon a gasket 30 thereby providing a very close 30 joint.

My improved refrigerator is especially designed by me for use in hotels and the like where it is desired to maintain low temperatures for certain articles of food and less 35 temperatures for others. This I have accomplished in a structure which is very compact and is easily supplied with refrigerant.

I have illustrated and described my improvements in an embodiment which I have 40 found very practical. I have not attempted to illustrate and describe certain modifications and adaptation which I contemplate

as I believe the disclosure made will enable those skilled in the art to which my 45 invention relates to embody or adapt the same as may be desired.

Having thus described my invention what I claim as new and desire to secure by Letters Patent is:

1. A refrigerator comprising a casing, a provision chamber at each end of said casing each provided with an inner wall having air circulating openings at the top and bottom thereof, a refrigerating chamber 55 disposed centrally within said casing, and a U-shaped refrigerant chamber comprising side and bottom walls disposed in spaced relation to the side and bottom walls of said refrigerating chamber, the side walls of said refrigerant chamber being disposed in downwardly diverging relation and in spaced relation to the said inner walls of said provision chambers and coacting therewith to provide air circulating passages with which said air circulating openings communicate.

2. A refrigerator comprising a casing, a provision chamber at each end of said casing, a refrigerating chamber disposed centrally within said casing, and a U-shaped refrigerant chamber comprising side and bottom walls disposed in spaced relation to the side and bottom walls of said refrigerating chamber, said provision chambers each being provided with an inner wall disposed in spaced relation to the side walls of said refrigerating chamber providing unobstructed air passages, there being circulating openings in the top and bottom of said provision chamber inner walls, such inner walls being otherwise imperforate.

In witness whereof, I have hereunto set my hand.

WILLIAM P. WILLSON.
